SEWING MACHINE

Frederick Lutz, Stuttgart, Germany, assignor to
 Union Special Maschinenfabrik, G. m. b. H.,
 Stuttgart, Germany

Application June 25, 1935, Serial No. 28,314

18 Claims. (Cl. 112—162)

This invention relates to sewing machines, particularly to sewing machines for forming over-edge seams, including both plain and scalloped or shell stitch seams, either from one or from 5 several threads.

My invention is directed toward simplifying and structurally refining machines of the kind referred to with a view toward making possible their operation at higher speeds than feasible 10 heretofore, and thereby attaining a correspondingly increased output from them. These advantages I secure in part as hereinafter set forth, through provision of stitch forming mechanism wherein three instrumentalities cooperate to perform 15 all the necessary functions for which four elements were required heretofore. These instrumentalities include a reciprocating needle, a non-thread carrying hook looper to draw loops of the needle thread below the throat plate of the machine, and a latch looper adapted to engage the needle thread above the throat plate and to draw loops of said thread around the edge of 20 the fabric and through previously formed loops, with incidental casting of such loops from its shank and then to take the loops from the hook looper before re-engaging the needle thread 25 above the throat plate in successive repetitions of the stitch forming cycle. In addition, my invention provides smoothly-operating, dynamically-balanced parts for actuating the hook looper and the latch looper in such manner as to draw only the required amount of the needle thread in predetermining tight seam loops of a definite size. As a consequence, I am able to 30 dispense with the special and complicated compensating thread take-ups used in looper sewing machines of ordinary construction.

Another object of my invention is to provide for the delivery of an auxiliary thread in such a 40 way that it will be taken only by the latch looper each time that the latter engages the needle thread above the throat plate as above stated, with resultant formation of a double loop fringe along the edge of the plain or shell stitch seam 45 produced in the machine.

Another object of my invention is to make it 50 possible to vary the timing of the feed means for adaptation of the sewing machines to the formation either of plain or shell stitch seams. This I secure, also as hereinafter more fully explained, by providing simple actuating parts for the feed element and by allocating said parts in the machine so that they are conveniently accessible for the purposes of ready interchange.

55 Other objects and attendant advantages of this

invention will be clear from the drawings, where-
 in Fig. I is a side elevation of a sewing machine
 conveniently embodying the present improve-
 ments, a portion of the base of the machine hav-
 ing been broken away to expose the mechanism 5
 at the interior.

Fig. II is a view drawn to a larger scale and
 showing the front elevation of the lower portion
 of the machine.

Fig. III is a fragmentary view likewise drawn 10
 to a larger scale, and showing the lower front
 portion of the machine in plan with the work-
 supporting plate removed.

Fig. IV is a detail sectional view taken as indi- 15
 cated by the arrows IV—IV in Fig. III and show-
 ing, in part, the means for actuating the latch
 looper.

Fig. V is a detail sectional view taken as indi- 20
 cated by the arrows V—V in Fig. III, and show-
 ing the means for actuating the feed dog of the
 machine.

Figs. VI—X are fragmentary perspective views 25
 showing how the needle and the hook and the
 latch loopers cooperate in forming a plain over-
 edge seam with the needle thread alone.

Fig. XI is a detail sectional view showing how 30
 the needle and the two loopers cooperate in forming
 an overedge seam with the needle thread and
 an auxiliary thread.

Figs. XII—XV illustrate different forms of 35
 seams capable of being formed with my improved
 sewing machine.

As herein shown, the sewing machine of my in- 40
 vention comprises a main shaft which is jour-
 naled in the lower part of the machine, and which
 is provided at one end with a pulley 2 for co-
 ordination by means of a belt (not shown) with a
 suitable source of power. Mounted on the main 45
 shaft 1 is an eccentric 3 whereof the upwardly-
 extending rod 4 is pivoted to a lever 5 by which
 reciprocating motion is imparted to the needle
 bar 6 of the machine. A pendant arm 7 of the
 lever 5 is relied upon to actuate the non-thread 50
 carrying hook looper 8 which operates beneath
 the throat plate of the machine, to draw a loop
 from the needle thread for presentation to the
 latch looper as later on explained, the interme-
 diate connections including a link 8a, and an os- 55
 cillating arm 8b on a rock shaft 8c which is
 obliquely arranged as shown in Fig. III so that
 the hook end of said looper swings at an angle
 crosswise of the path of the seaming needle of
 the machine above said throat plate.

To the left hand end of the main shaft 1 (Fig. 60)
 II is secured a crank 10, which, through a link

11 and a rocker arm 11a, actuates the latch looper carrier 12. A yoke 13 affords journal support for an obliquely-disposed oscillating shaft 14 whereto the latch looper carrier 12 is fixed, said yoke being in turn secured to another shaft 15, which, see Fig. II, is located beneath the main shaft 1, and oscillated laterally through engagement of a fork 16 thereon with a rotary cam 17 on the main shaft 1. The latch looper 18 is indicated at 18, and, as shown, has a curved body or shank with a hook end adapted to be closed by a pivoted latch after the manner of a knitting machine needle. Incident to rotation of the main shaft 1, the latch looper 18 is bodily oscillated substantially at right angles to the swing of the hook looper 8 (see Fig. III) toward and away from the seaming needle by action of the rotary cam 17 upon the yoke 13, and concurrently moved up and down through influence 20 of the crank 11 upon the arm 11a on the oscillating shaft 14 which supports the latch looper carrier 12, these combined motions causing the hook end of the latch looper to trace a short arc around the edge of the fabric in a manner 25 more clearly set forth hereinafter.

An eccentric 19 on the main shaft 1 communicates motion, through a link 20, to a rocker 21 by which the feed bar of the machine is horizontally reciprocated, said feed bar being moved 30 up and down at the ends of its horizontal strokes in opposite directions by the action of the circumferential cam groove 23 of a rotary cam 24 which revolves about a vertical screw stud 24a threaded into the base of the machine and 35 which is driven by means of a worm gear couple 25, 26 from the main shaft 1, see Figs. III and V. As shown, the cam groove 23 is engaged by a stud 27 at the end of the lever 28, which latter is fulcrumed for free oscillation on the rock 40 shaft 15, and connected with the feed bar 22 by means of a link 29. The feed dog 30 on the bar 22 is thus actuated to intermittently progress the fabric across the work support of the machine for seaming by the needle. Attention is directed to the fact that the gear wheel 26 is 45 located in an interval between the main shaft 1 and the feed bar rock shaft 21a, and between the feed bar link 20 and the feed bar 22, where it is conveniently accessible from above, and further to the fact that the rotary cam 24 is 50 made separate from the gear wheel 26 and secured thereto by two screws 26a, see Fig. III. This construction permits ready interchange of the parts when the timing of the feed mechanism is to be altered in adapting the machine 55 for scallop or shell stitch seaming as presently described.

As shown in Figs. VI-X the throat plate 34 of the machine provides a fixed stitch tongue 35 which is aligned in the direction of feed and over which loops of the needle thread are formed by the hook and latch loopers 8 and 18 in the manner about to be disclosed.

The operation of the machine in making a 65 plain overedge seam is as follows:

By the combined action of the eccentric 19 and the rotary cam 17 on the shaft 1, the latch looper 18 is actuated in such manner that its hook end describes a comparatively short arc angularly in the direction of feed closely about the side edge of the stitch tongue 35, this action being possible as a result of the curving of the shank or body of said looper, and advantageous in that only the required amount of thread is drawn from the needle to produce small tight

seam loops of a predetermined size without the need of additional means to absorb excessive slack occasioned by the movements of the loopers as in prior art sewing machines. The stitch forming cycle begins as shown in Fig. VI when the latch looper 18 is in fully advanced position relative to the needle with its hook end above the throat plate 34 immediately adjacent the path of said needle. As the needle 31 descends, it lays its thread 37 into the hook of the latch looper 18 as shown in Fig. VII, while said latch looper, in moving downward in close proximity to the stitch tongue 35 draws a loop 31a of said thread around the edge of the fabric and through two previously formed hook and latch looper loops 37b and 37c temporarily held on said stitch tongue after the manner shown in Fig. VIII. As the latch looper 18 completes its outward and downward movement, its latch closes over the new loop 31a, with incidental casting of the two 20 old loops 37b and 37c as shown in Fig. IX, this occurring just about the time that the needle 31 reaches its lowermost position. As the needle 31 starts its ascent, the hook looper 8 engages the needle thread 37 also as shown in Fig. IX, 25 and, in moving away from the needle, draws a loop 31d angularly crosswise of the bottom of the stitch tongue 35, while the latch looper 18 begins to move upward toward the needle through said loop 31d, thereby taking said loop 30 as shown in Fig. X, the needle in the meanwhile ascending to its uppermost position concurrently 35 with the latch looper for repetition of the stitch forming cycle. With the feed dog 30 timed to function once for each stroke of the needle 35 as ordinarily, a plain overedge seam such as shown in Fig. XII is produced as a result of the cooperation of the hook and latch looper 8 and 18 with said needle as above described.

By providing a feed eye 38 on the needle bar 6 40 of the machine, as shown in Fig. XI, to feed an auxiliary thread 39 so that it may be taken by the latch looper 18 when the latter moves upward to take the needle yarn 37, it is possible to produce an overedge seam such as is shown in Fig. 45 XIII having an edge fringe thickened by the additional loops 39a of said auxiliary thread. In this connection it is to be noted that the hook looper 8 never engages the auxiliary thread 39; and it is for this reason that the loops 39a formed 50 from said thread arrange themselves along the edge of the stitching.

A rotary cam 24 with a differently formed groove 23, or worm gears 25, 26 of a different ratio may be employed to change the timing of the feed dog 30 so as to shift the fabric after the formation of several stitches. With use of the needle thread 37 only there results a scallop or shell stitch seam such as is shown in Fig. XIV; while, by using both the threads 37 and 39 with 60 changed operation of the feed dog 30, it is possible to form a scallop or shell stitch seam such as is shown in Fig. XV, with the added loops 39a of the auxiliary thread doubled with the edge loops formed from the needle thread. Due to the 65 ready accessibility of the gearing 25, 26 and the cam 24, the change from one condition of operation to the other can obviously be accomplished with comparative ease and a minimum loss of time.

Having thus described my invention, I claim:

1. A sewing machine comprising a reciprocating needle; a non-thread-carrying looper to draw loops from the needle thread at one side of the fabric being seamed; and a latch looper to draw 75

loops from the needle thread at the other side of the fabric, and, after drawing such loops, to take the loops from the first mentioned looper.

2. A sewing machine comprising a reciprocating needle; a non-thread-carrying looper to draw loops from the needle thread at one side of the fabric being seamed; a latch looper to draw loops from the needle thread at the other side of the fabric, and, after drawing such loops, to take the loops from the first mentioned looper; and means to actuate the two loopers to draw only sufficient thread for tight seam loops of the desired size.

3. A sewing machine comprising a reciprocating needle; a fixed stitch tongue; a non-thread-carrying looper to draw loops from the needle thread beneath the stitch tongue; a latch looper to draw loops from the needle thread above the stitch tongue, and, after drawing such loops, to take the loops from the first mentioned looper; and means to actuate the two loopers to draw only sufficient thread for seam loops of the desired size.

4. A sewing machine comprising a reciprocating needle; a fixed stitch tongue aligned in the direction of feed; a non-thread-carrying looper to draw loops from the needle thread below the stitch tongue; a latch looper to draw loops from the needle thread above the stitch tongue, and, after drawing such loops, to take the loops from the first mentioned looper; means for actuating the first mentioned looper to draw only sufficient thread for seam loops of the desired size; and means for actuating the latch looper such that its hook end describes a short arc around the edge of the stitch tongue likewise for seam loops of the desired size.

5. A sewing machine comprising a reciprocating needle; a throat plate; a hook looper operative beneath the throat plate; means for actuating the hook looper to draw loops from the needle thread; a latch looper; and actuating means for moving the latch looper to draw a loop of the needle thread above the fabric, around the fabric edge and through a pair of previously formed loops thereon with incident casting of said loops, and then to take the loop from the hook looper aforesaid before reengaging the needle thread above the throat plate in initiating another stitch forming cycle.

50 6. A sewing machine comprising a reciprocating needle; a throat plate affording a stitch tongue; a hook looper operative beneath the throat plate; means for actuating the hook looper to draw loops of the needle thread under the stitch tongue; a latch looper; and means for actuating the latch looper so that its hook end traces an arc angularly to the direction of feed and in close proximity to the edge of the stitch tongue, and in so moving, engages the needle thread above the throat plate to draw a loop therefrom downward around the edge of the fabric and through previously formed loops on its shank, with incidental casting of such previous loops, and thereafter takes the loop from the hook looper before reengaging the needle thread above the throat plate to initiate another stitch forming cycle.

70 7. A sewing machine comprising a reciprocating needle; a throat plate; a hook looper operative beneath the throat plate; means for oscillating the hook looper to form loops from the needle thread; a latch looper; a carrier for said latch looper; a laterally oscillating support to which said latch looper is pivoted with capacity for up and down movement; and means for oscillating the support and for concurrently swinging the

latch looper about its pivot axis on the support whereby it is caused to draw a loop from the needle thread above the throat plate, around the edge of the fabric and through two previously formed loops thereon with incident casting of said loops, and then to take the loop from the hook looper aforesaid before re-engaging the needle thread above the throat plate in initiating another stitch forming cycle.

8. A sewing machine comprising a reciprocating needle; a throat plate; a hook looper operative beneath the throat plate; means for oscillating the hook looper about an axis oblique to the direction of feed to engage the needle thread and draw loops therefrom; a latch looper; a support for the latch looper oscillating laterally about an axis aligned in the direction of feed; an oblique axis on the support whereto the latch looper is secured with capacity for up and down movement incident to being swung at substantially right angles to the movement of the hook looper; and means for oscillating the support and for concurrently rocking the latch looper on its pivot axis so that it is caused to draw a loop from the needle thread above the throat plate around the edge of the fabric and through two previously formed loops on its shank, with incident casting of such loops, and then to take the loop from the hook looper aforesaid before re-engaging the needle thread above the throat plate in initiating another stitch forming cycle.

9. A sewing machine comprising a needle bar with a reciprocating needle carrying a seaming thread; an eye on the needle bar for guiding an auxiliary thread; a throat plate; a hook looper operative beneath the throat plate; means for actuating the hook looper to draw loops from the needle thread below the throat plate; a latch looper; and actuating means for moving the latch looper to concurrently draw loops from the needle and auxiliary threads above the throat plate, through previously formed loops thereon with incident casting of the latter loops, and then forwardly and upwardly to take the loop from the hook looper aforesaid before re-engaging the needle thread and the auxiliary thread above the throat plate.

10. A sewing machine comprising a reciprocating needle; a throat plate with a fixed stitch tongue aligned in the direction of feed; a hook looper operative beneath the throat plate; means for actuating the hook looper to draw loops from the needle thread around the bottom of the stitch tongue; a latch looper; and actuating means for moving the latch looper downwardly and outwardly away from the needle above the throat plate to draw a loop of the needle thread around the stitch tongue and through a pair of previously formed loops thereon with incident casting of the latter loops, then forwardly and upwardly to take the loop from the hook looper aforesaid before re-engaging the needle thread above the throat plate.

11. A sewing machine comprising a reciprocating needle; a non-thread carrying looper for drawing loops from the needle thread at one side of the fabric being seamed; a latch looper for drawing loops from the needle thread at the other side of the fabric, and, after drawing such loops, taking the loops from the first mentioned looper; and means for feeding an auxiliary yarn so as to be taken by the latch looper at the same time that the latter engages the needle thread.

12. In a sewing machine comprising a reciprocating needle, a feed dog, and means for recipro-

- cating the feed dog horizontally; the combination of a non-thread carrying looper for drawing loops from the needle thread at one side of the fabric being seamed, a latch looper for drawing loops from the needle thread at the other side of the fabric and after drawing such loops taking the loops from the first mentioned looper, and a rotary cam-actuated lever for imparting lift movements to the feed dog.
- 10 13. In a sewing machine comprising a reciprocating needle, a feed dog, means for reciprocating the feed dog, a rotary shaft, and a rocker actuated by an eccentric on the shaft for reciprocating the feed dog horizontally; the combination of 15 a non-thread carrying looper for drawing loops from the needle thread at one side of the fabric being seamed, a latch looper for drawing loops from the needle thread at the other side of the fabric, and, after drawing such loops taking the loops from the first mentioned looper, means whereby the two loopers are operated from the shaft aforesaid, a rotary cam driven by gearing from the shaft, and a lever operated by the rotary cam moving the feed dog up and down.
- 20 14. In a sewing machine comprising a reciprocating needle, a rotary shaft, a feed dog, a rocker actuated by an eccentric on the shaft which reciprocates the feed dog horizontally; the combination of a non-thread carrying looper for drawing 25 loops from the needle thread at one side of the fabric being seamed, a latch looper for drawing loops from the needle thread at the other side of the fabric and after drawing such loops taking the loops from the first mentioned looper, connections 30 whereby the two loopers are operated from the rotary shaft, a rotary cam on said shaft, a lever operated by the rotary cam for moving the feed dog up and down, a worm gear to which the rotary cam is detachably secured, and a worm 35 on the main shaft for driving the worm wheel.
- 40 15. In a sewing machine, a reciprocating needle, a transversely reciprocating thread manipulating element cooperating with the needle at one side of the fabric being sewed, and a transversely-reciprocating latch looper cooperating with the needle at the other side of the fabric in the formation of stitches.
16. In a sewing machine, a reciprocating needle, 5 a transversely reciprocating thread manipulating element cooperating with the needle at one side of the fabric being sewed, a transversely-reciprocating latch looper cooperating with the needle at the other side of the fabric in the formation of 10 stitches, and means for advancing the fabric relative to the needle each time only after several actuations of the needle, the thread manipulating element and the looper to determine formation of shell stitch effects. 15
17. A sewing machine comprising a reciprocating needle; a non-thread carrying looper for drawing loops from the needle thread at one side of the fabric being seamed; a latch looper for drawing loops from the needle thread at the other 20 side of the fabric, and, after drawing such loops, taking the loops from the first mentioned looper; means for feeding an auxiliary yarn so as to be taken by the latch looper at the same time that the latter engages the needle thread; and means 25 for advancing the fabric relative to the needle each time only after several actuations of the needle and the two loopers whereby the formation of shell stitch effects is determined.
18. In a sewing machine comprising a reciprocating needle, a feed dog and means for horizontally reciprocating said feed dog in synchronism with the needle; the combination of a non-thread carrying looper cooperating with the needle at one 30 side of the fabric being sewed, a latch looper to 35 cooperate with the needle at the opposite side of the fabric, and means for imparting lift movements to the feed dog such that the fabric is advanced each time only after several actuations of the needle and the two loopers whereby the formation of shell stitch effects is determined. 40

FREDERICK LUTZ.
